UNITED STATES PATENT OFFICE.

MERRILL STEVENS, OF TOPEKA, KANSAS.

INTEREST-COMPUTING DEVICE.

1,209,349.

Specification of Letters Patent. Patented Dec. 19, 1916.

Application filed July 3, 1916. Serial No. 107,390.

To all whom it may concern:

Be it known that I, MERRILL STEVENS, a citizen of the United States, residing at Topeka, in the county of Shawnee and State 5 of Kansas, have invented a new and useful Interest-Computing Device, of which the following is a specification.

The present invention is a device for calculating or computing interest, and it is the 10 object of the invention to provide a very simple and inexpensive yet thoroughly practical, convenient and efficient device of that character for readily ascertaining with absolute accuracy the interest on various 15 amounts at any rate of interest for any number of days or between two given dates, as well as quickly determining the number of days between any two dates or determining the due date from a certain date 20 by any given number of days for which a note or other period is to run.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

The invention is illustrated in the accompanying drawing, wherein:

Figure 1 is a plan view of the device. Fig. 2 is an enlarged fragmental plan view 35 thereof to illustrate the index tab and adjoining portions. Fig. 3 is a section on the line 3—3 of Fig. 2. Fig. 4 is a bottom view of the portions shown in Fig. 2. Fig. 5 is a section on the line 5—5 of Fig. 1 illustrating the pivot.

In carrying out the invention, there are provided two superposed disks 1 and 2 composed of card board or any other suitable 45 material, the upper disk 2 being of slightly smaller diameter than the lower disk 1, and the two disks being provided with central apertures receiving a bushing 3 having suitable washers 4 upon the ends thereof. A clip or other fastener 5 is engaged

through the bushing 3 and serves as a pivot for connecting the two disks whereby they can be rotated relative to one another.

The upper disk 2 has printed or otherwise provided thereon a concentric circular line 55 6, and radial lines 7 extending from the line 6 to the margin of the disk and dividing the marginal portion of said disk into twelve month divisions, one for each month of the year. The disk 2 is further provided with 60 a second circular line 9 between the line 6 and the margin of the disk, and the annular column between the line 9 and margin of the disk is provided with radial lines 10, sub-dividing each month division 8 into the 65 proper number of day sub-divisions, and said sub-divisions of each month division are numbered consecutively from 1 upward to 28, 30 or 31 according to the number of days in the particular month. 70

The day sub-divisions are all of uniform size, while the month divisions are of a length proportional to the number of days thereof.

The lower disk 1 is provided upon its upper surface with a circular line 11 between the margin of the two disks, and the upper surface of the disk 1 is provided with radial lines 12 between the margins of the two disks. The line 11 provides two annular 80 columns divided by the lines 12 into the spaces 13 and 14, respectively. The spaces 13 are numbered from 1 to 365 consecutively, this being an intermediate column between the inner column upon the upper 85 surface of the upper disk 2, and the outer column upon the disk 1 adjacent the margin thereof. Said outer column of the disk 1 has its spaces 14 bearing the interest in dollars on \$1000 at one per cent. for a number of days corresponding to the number of days of the year indicated by the numerals in the intermediate column of spaces 13. The outer column can have the interest indicated thereon in other units upon various 90 sums and at various rates of interest, but the foregoing is exceedingly practical in use. 95

The lower disk 1 is provided with a slit 15 whose terminals extend radially along certain lines 12, and whose intermediate por- 100

tion extends inwardly beyond the margin of the upper disk. This slit 15' provides an inwardly projecting index tab 15 which is sprung upwardly so as to overlap and rest upon the upper surface of the marginal portion of the upper disk 2. One edge of the tab 15 is on the division line between the numerals 1 and 365 of the intermediate column, and the tab is provided at that edge and adjacent its free inner end with an angular notch 16 providing an offset edge 17. The tab 15 is preferably provided thereon along the edge 17 with an area 18 colored red or any other suitable color to attract attention to said edge, and to facilitate the setting of the disk 2. The marginal portion of the disk 2 fits snugly underneath the tab 15, and is held snugly upon the disk 1 by the tension of said tab. Said tab tends to swing into the plane of the disk 1, and in this manner, the two disks are held in any position to which they are rotated relative to one another.

In the table composed of the three columns, no account is taken of February 29, and for terms of days in leap years, when such date is passed, one day should be added, which can be readily done by moving the disk 2 ahead to bring the next day number within the notch 16. For terms of days in leap years, the annular table upon the lower or back surface of the disk 1 should be consulted. Thus, the back or lower surface of the disk 1 is provided with the annular line 11', radial lines 12', and annular columns 13' and 14' corresponding to the parts designated 11, 12, 13 and 14 upon the upper surface of the disk 1, with the exception that in the table upon the back of the disk or card 1, the columns 13' and 14' are divided into 366 spaces for leap year, and the interest for spaces 14' is figured accordingly.

The use of the present device is best explained by examples:

Example 1: Wanted—interest at 5% on \$800 from Dec. 1 to Aug. 31: Rotate the disk 2 to bring the designation Dec. 1 in the notch 16 of tab 15 next to the offset edge 17, and the designation Aug. 31 will be found registering with the numeral 273 on the middle column. 273 is the number of interest days from Dec. 1 to Aug. 31. Adjacent the numeral 273 in the middle column appears in the outer circle 7.479452—interest

on \$1000 for 273 days on a 365-day year is 66 at 1%:

$$\$800 = .8 \text{ of } \$1000$$

$$5\% \times .8 = 4\%$$

$4 \times 7.479452 = \$29.92$, all of which is 60 readily computed mentally from the table.

Example 2: Wanted—due date on note for sixty days dated May 1: Bring the designation May 1 within the notch 16 adjacent the offset edge 17, and the designation 60 in the middle column will indicate the due date June 30 on the inner column.

Example 3: Wanted—the number of interest days between Nov. 13 and Jan. 27: Bring the designation Nov. 13 within the notch 16, and the designation Jan. 27 will indicate 75 on the middle column—the number of interest days between said dates.

In the event of leap year, when the interest period runs past February 29, one number is added to the indicated number of the middle column, and then the table on the back of the disk or card 1 is consulted for the interest unit.

Having thus described the invention, what is claimed as new is:

A computing device embodying a card and a disk mounted for rotation thereon, said card having a slit whose terminals project radially outward, said slit providing an inwardly projecting spring index tab overlapping the margin of the disk to press the disk upon the card, the card having radial lines providing an annular column of spaces adjacent to the edge of the disk, said spaces being graduated starting from one edge of the tab, the disk having radial lines providing an annular column of spaces at the edge of the disk co-operable with the aforesaid spaces, said tab having a notch at 95 said edge and adjacent to its free end providing an offset edge with which the lines of the disk are registrable, said notch being of a size to receive one of the spaces of the annular column of the disk. 100

In testimony that I claim the foregoing as my own, I have hereto affixed my signature in the presence of two witnesses.

MERRILL STEVENS.
